[57] CLAIM

The ornamental design for a toilet seat handle, as shown and described.

DESCRIPTION

FIG. 1 is a top plan view of a toilet seat handle showing my new design;

FIG. 2 is a bottom plan view thereof;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a perspective view of the toilet seat handle located on the underneath side of a toilet seat, the portions of the toilet and the toilet seat shown in broken lines are for illustrative purposes only, and form no part of the claimed design.

1 Claim, 2 Drawing Sheets

FIG. 7
